UNITED STATES PATENT OFFICE.

SIMO GJUKIC, OF CAMEO, COLORADO.

DOORLOCK.

Application filed January 8, 1925. Serial No. 1,193.

To all whom it may concern:

Be it known that I, Simo Gjukic, a citizen of the United States, residing at Cameo, in the county of Mesa and State of Colorado, 5 have invented certain new and useful Improvements in Doorlocks, of which the following is a specification.

This invention relates to certain new and useful improvements in door locks of the 10 type embodying a knob operated latch bolt and has for one of its objects to provide key operated devices associated with the latch bolt for holding the same in its extended position housed within a keeper.

15 A further object of the invention is to provide in a door lock of the type above set forth, novel key operated devices requiring the use of a special type of key to operate the same and permit operation or sliding 20 movement of the latch bolt thru the medium of a knob spindle.

A still further object of the invention is to provide in a door lock comprising in combination with a latch bolt capable of being locked in a projected position, a sliding lock bolt to be projected or retracted incident to the operation of the devices that control the movement of the latch bolt.

With the above general objects in view 25 and others that will appear as the nature of the invention is better understood, the same consists of the novel form, combination, and arrangement of parts hereinafter more fully described, shown in the accompanying drawings and claimed.

In the drawings, wherein like reference characters designate corresponding parts throughout the several views,

Figure 1 fragmentarily illustrates in vertical section, a door and frame with the cover plate of the door lock removed and showing the tensioned latch bolt locked in its projected position with the nose thereof housed in its keeper socket and further showing the 45 lock bolt projected,

Figure 2 is a sectional view similar to Fig. 1 showing the latch and lock bolts in their retracted positions,

Figure 3 is a horizontal sectional view 50 showing the upper side of the tensioned latch bolt,

Figure 4 is a fragmentary vertical sectional view,

Figure 5 is an elevational view of the 55 outer side of the lock casing designed to provide for the key operation of the lock,

Figure 6 is an edge elevational view of the door with the lock in position,

Figure 7 is an elevational view of the inner side of the lock casing showing the 60 manually operable lever for shifting the lock mechanism,

Figure 8 is a detail sectional view showing the devices for controlling sliding movement of the latch bolt.

Figure 9 shows side and end elevational views of the key receiving barrel, and

Figure 10 is a fragmentary elevational view of the outer face plate of the lock casing with the rotatable key receiving barrel 70 removed.

The door lock is associated with a door 1 that has its free swinging edge moving into abutting relations with the door frame 2 and the lock embodies a casing having a bottom wall 1, side walls 2 and 3, end walls 4 and 5 and a movable top wall 6 that is retained in position by the screw 7 or other suitable fastening devices. The lock casing is set into an opening 8 formed in the door with the end wall 5 lying flush with the adjacent edge of the door 1 and having end extensions 9 that are anchored to the door as shown in Figs. 1 and 2. A keeper plate 10 is similarly secured to the adjacent portion of the door frame and the end wall 3 of the lock casing and keeper plate are provided with registering openings 11 and 12 that form communication between the interior of the lock casing and latch bolt and lock bolt sockets 13 90 and 14 respectively, formed in the door frame 2.

A bifurcated lug 15 projecting perpendicularly from the bottom wall 1 of the casing constitutes a guide for the shank of a latch bolt 16, the forward end of the bolt 16 being provided with the usual tapering latch nose or head 17 adapted to be projected through the latch openings 11 for reception in the keeper socket 13, the latch head 17 being 100 preferably formed with a threaded socket to receive the adjacent threaded end of the latch bolt shank 16 and normally influenced in a direction toward the openings 11 by the coil spring 18 surrounding the latch bolt shank between the bifurcated lug 15 and the latch head 17. The rear end of the latch bolt shank is of frame construction and embodies side bars 19 and 20 connected by cross heads 21 and 22, the latter being of arcuate 110 formation as shown in Figs. 1 and 2.

The latch bolt is reciprocated through the

2
medium of a knob spindle and shackle carried thereby that is associated with the arcuate cross head 22 of the latch bolt frame, the reference numeral 23 designating a knob 5 spindle extending through the bottom and top walls 1 and 6 of the lock casing with a knob 24 upon each end thereof, the knob spindle 23 extending between the side bars 19 and 20 of the latch bolt frame and having 10 a side extension lug 25 projecting between shoulders 26 formed on the double shackle 27 for locking the shackle thereto, the rear curved edge 27^a of the shackle engaging the curved cross head 22 as shown in Fig. 1. 15 The knob spindle 23 rotatably projects through openings provided therefor in the door 1 and has associated therewith, inner and outer face plates 28 and 29 respectively that are secured as at 30 to the door. It will 20 therefore be seen that when the knobs 24 are turned in either direction, the shackle 27 carried by the knob spindle will engage the curved cross head 22 as shown in Fig. 2 for retracting the latch bolt against the tension of the spring 18.

Devices are associated with the sliding latch bolt for holding the same in a projected locked position with the latch head 17 retained in the keeper socket 13 and include 30 a bifurcated lug 31 projecting perpendicularly from the bottom wall 1 of the casing and through which a sliding latch member 32 extends for reciprocating movement at right angles to the longitudinal axis of the 35 latch bolt shank 16. The latch member 32 carries a head 33 that is adapted to be received in the socket 34 formed in the adjacent side of the frame bar 20 and is normally influenced in a direction toward said bar by 40 the coil spring 35 surrounding the latch member 32 between the head 33 and bifurcated lug 31. The head 33 is guided in its movements by the spaced lugs 33^a to prevent lateral movement of the head. 45 The operating means for the latch member 32 embodies a cylindrical block 36 rotatably supported in openings formed in the bottom and top walls 1 and 6 of the lock casing as shown in Fig. 8 with the inner end of the 50 block extending into an opening 37 provided in the door 1 while a handle or finger piece 38 positioned outwardly of the face plate 28 is secured as at 39 to the adjacent end of the rotatable block 36 for rotating 55 the same. An eccentric cam portion 40 is carried by the block 36 within the lock casing and is enclosed by a circular strap or band 41 that is pivotally connected as at 42 to the adjacent end of the latch member 32 outwardly of the bifurcated lug 31. The end of 60 the block 36 supported in the top wall of the lock casing is provided with a circular recess 43 having a key receiving socket 44 in the bottom wall of the recess at one side 65 thereof as shown by dotted lines in Fig. 8.

As shown more clearly in Figs. 8 to 10, the face plate 29 carries a tubular bearing 45 extending into the opening 46 formed in the door 1 while an enlargement 47 is formed at one side of the bearing as shown in Figs. 70 8 and 10. The other end of the tubular bearing adjacent the outer side of the face plate 29 is tapered as at 48 to be engaged by the tapered end 49 of the key receiving rotatable barrel 50. The reduced inner end 75 51 of the barrel is received in the recess 43 and the barrel is rotatable in the sleeve 45 and block 36, the barrel being retained in position by the ring or band 52 seated in an annular groove formed in the barrel, the band being split and having one of its spaced ends forming an outwardly extending lug 53 that projects into the groove 54 in one side of the tubular bearing 45. A set screw 55 threaded through the bearing enlargement 47 engages the band to prevent longitudinally shifting movement of the key receiving barrel. The barrel 50 is provided with a longitudinally extending key receiving slot 56 and in order to place a key in the slot, it is necessary that the barrel be rotated to position the spaced ends of the band 52 out of registration with the slot and at which time the slot 56 registers with the key receiving socket in the adjacent end of the 80 rotatable block 36. With the key so positioned, the barrel and block are simultaneously rotated and the eccentric cam 40 housed by the band 41 causes a lowering and laterally shifting movement of the band as indicated in Fig. 2 to retract the latch head 33 from the notch or socket 34 in the adjacent bar 20 of the latch bolt frame, and at which time, rotation of the knob spindle 23 85 shifting the shackle 27 retracts the sliding latch bolt 16. The block 36 is operated from the inner side of the door by the handle or finger piece 38 and is operable by a key from the outer side of the door. The latch member 32 may be retained in the retracted position shown in Fig. 2, when it is desired that the door remain in an unlocked condition.

The casing houses a lock bolt 57 that is 90 slidably mounted in a guide 58, the nose of the lock bolt projecting through the casing opening 12 to be received in the keeper socket 14 as shown in Figs. 1 and 2, there being a pivotal connection 59 between the inner end of the lock bolt 57 and the band 41. When the latch member 32 is positioned for holding the latch bolt 16 in its locked position, the lock bolt 57 is automatically shifted to its locked position at the same time, the lock bolt being automatically retracted when the latch member 32 is shifted to a position to permit free operation of the latch bolt.

From the above detail description of the 95 invention, it is believed that the construc-

tion and operation thereof will at once be apparent, and while there is herein shown and described the preferred embodiments of the present invention, it is nevertheless to be understood that minor changes may be made therein without departing from the spirit and scope of the invention as claimed, such as the substitution of different types of key barrels having key receiving slots of different configurations requiring special keys for the manipulation of the lock mechanism.

What is claimed as new is:—

1. In a door lock, a lock casing, a tensioned sliding latch bolt in the casing, a tensioned latch member movable into engagement with the latch bolt to hold the same in a projected position, manually operable means for the latch member including a rotatable cam, and a band carried by the latch member inclosing the cam.

2. In a door lock, a lock casing, a tensioned sliding latch bolt in the casing, a tensioned latch member movable into engagement with the latch bolt to hold the same in a projected position, manually operable means for the latch member including a rotatable cam, a band carried by the latch member inclosing the cam, and a finger piece at the inner side of the door for operating the cam.

3. In a door lock, a lock casing, a tensioned sliding latch bolt in the casing, a tensioned latch member movable into engagement with the latch bolt to hold the same in a projected position, manually operable means for the latch member including a rotatable cam, a band carried by the latch member inclosing the cam, and said cam being key-operated from the outer side of the door.

4. In a door lock, a lock casing, a tensioned sliding latch bolt in the casing, a tensioned latch member movable into engagement with the latch bolt to hold the same in a projected position, manually operable means for the latch member including a rotatable cam, a band carried by the latch member inclosing the cam, a finger piece at the inner side of the door for operating the cam, and said cam being key-operated from the outer side of the door.

5. In a door lock, a lock casing, a tensioned sliding latch bolt in the casing, a tensioned latch member movable into engagement with the latch bolt to hold the same in a projected position, manually operable means for the latch member including a rotatable cam, a band carried by the latch member inclosing the cam, and a rotatable barrel associated with the outer end of the cam designed to receive a key that engages the cam for rotating the same.

6. In a door lock, a lock casing, a tensioned sliding latch bolt in the casing, a tensioned latch member movable into engagement with

the latch bolt to hold the same in a projected position, manually operable means for the latch member including a rotatable cam, a band carried by the latch member inclosing the cam, a finger piece at the inner side of the door for operating the cam, and a rotatable barrel associated with the outer end of the cam designed to receive a key that engages the cam for rotating the same.

7. In a door lock, a lock casing, a tensioned sliding latch bolt in the casing, a tensioned latch member movable into engagement with the latch bolt to hold the same in a projected position, manually operable means for the latch member including a rotatable cam, a band carried by the latch member inclosing the cam, a rotatable barrel associated with the outer end of the cam designed to receive a key that engages the cam for rotating the same, said barrel having a key receiving slot and an annular groove in the periphery traversing the slot, and a split ring seated in the groove with the end spaced a distance equal to the diameter of the key receiving slot.

8. In a door lock, a lock casing, a tensioned sliding latch bolt in the casing, a tensioned latch member movable into engagement with the latch bolt to hold the same in a projected position, manually operable means for the latch member including a rotatable cam, a band carried by the latch member inclosing the cam, a finger piece at the inner side of the door for operating the cam, a rotatable barrel associated with the outer end of the cam designed to receive a key that engages the cam for rotating the same, said barrel having a key receiving slot and an annular groove in the periphery traversing the slot, and a split ring seated in the groove with the end spaced a distance equal to the diameter of the key receiving slot.

9. In a door lock, a lock casing, a tensioned sliding latch bolt in the casing, a tensioned latch member movable into engagement with the latch bolt to hold the same in a projected position, manually operable means for the latch member including a rotatable cam, a band carried by the latch member inclosing the cam, a rotatable barrel associated with the outer end of the cam designed to receive a key that engages the cam for the rotating the same, said barrel having a key receiving slot and an annular groove in the periphery traversing the slot, a split ring seated in the groove with the end spaced a distance equal to the diameter of the key receiving slot, and means for holding the split ring against rotation upon movement of the barrel.

10. In a door lock, a lock casing, a tensioned sliding latch bolt in the casing, a tensioned latch member movable into engage-

ment with the latch bolt to hold the same in a projected position, manually operable means for the latch member including a rotatable cam, a band carried by the latch member inclosing the cam, a finger piece at the inner side of the door for operating the cam, a rotatable barrel associated with the outer end of the cam designed to receive a key that engages the cam for rotating the same, said barrel having a key receiving slot and an annular groove in the periphery traversing the slot, a split ring seated in the groove with the end spaced a distance equal to the diameter of the key receiving slot, and means for holding the split ring against rotation upon movement of the barrel.

11. In a door lock, a lock casing, a tensioned sliding latch bolt in the casing, a tensioned latch member movable into engagement with the latch bolt to hold the same in a projected position, manually operable means for the latch member including a rotatable cam, a band carried by the latch member inclosing the cam, a rotatable barrel associated with the outer end of the cam designed to receive a key that engages the cam for rotating the same, said barrel having a key receiving slot and an annular groove in the periphery traversing the slot, a split ring seated in the groove with the end spaced a distance equal to the diameter of the key receiving slot, and a sliding lock bolt having a pivotal connection with the band.

12. In a door lock, a lock casing, a tensioned sliding latch bolt in the casing, a tensioned latch member movable into engagement with the latch bolt to hold the same in a projected position, manually operable means for the latch member including a rotatable cam, a band carried by the latch member inclosing the cam, a finger piece at the inner side of the door for operating the cam, a rotatable barrel associated with the outer end of the cam designed to receive a key that engages the cam for rotating the same, said barrel having a key receiving slot and an annular groove in the periphery traversing the slot,

a split ring seated in the groove with the end spaced a distance equal to the diameter of the key receiving slot, and a sliding lock bolt having a pivotal connection with the band.

13. In a door lock, a lock casing, a tensioned sliding latch bolt in the casing, a tensioned latch member movable into engagement with the latch bolt to hold the same in a projected position, manually operable means for the latch member including a rotatable cam, a band carried by the latch member inclosing the cam, a rotatable barrel associated with the outer end of the cam designed to receive a key that engages the cam for rotating the same, said barrel having a key receiving slot and an annular groove in the periphery traversing the slot, a split ring seated in the groove with the end spaced a distance equal to the diameter of the key receiving slot, means for holding the split ring against rotation upon movement of the barrel, and a sliding lock bolt having a pivotal connection with the band.

14. In a door lock, a lock casing, a tensioned sliding latch bolt in the casing, a tensioned latch member movable into engagement with the latch bolt to hold the same in a projected position, manually operable means for the latch member including a rotatable cam, a band carried by the latch member inclosing the cam, a finger piece at the inner side of the door for operating the cam, a rotatable barrel associated with the outer end of the cam designed to receive a key that engages the cam for rotating the same, said barrel having a key receiving slot and an annular groove in the periphery traversing the slot, a split ring seated in the groove with the end spaced a distance equal to the diameter of the key receiving slot, means for holding the split ring against rotation upon the movement of the barrel, and a sliding lock bolt having a pivotal connection with the band.

In testimony whereof I affix my signature.

SIMO GJUKIC.
